UNITED STATES PATENT OFFICE.

WALTER BUCKERIDGE, OF PERTH, AUSTRALIA.

SELECTIVE-CARD CABINET.

Application filed June 15, 1927, Serial No. 199,080, and in Australia April 11, 1927.

This invention relates to a selective card cabinet.

When using an index that includes a large number of cards, it is a matter of some trouble to find any particular card that may be required. Furthermore, the operation takes a fair amount of time, and is subject to the possibility that a card may have been misplaced, when the time taken is considerably prolonged.

The present invention relates to a selective card cabinet, by means of which on operating certain elements, the required card comes out of the cabinet, no matter in what relative position it may have been placed.

The invention will readily be understood by reference to the accompanying drawings, in which:—

Figure 1 is a front elevation of a card cabinet, (minus the cards):—

Fig. 2 is a plan thereof, in which, however, the pivots have been omitted for the sake of clearness:—

Fig. 3 is a perspective view of the inverted cabinet as it will appear when a card in the name of "W. Smith" is being discharged:—

Fig. 4 is a sectional side elevation of so much of the cabinet as is necessary to illustrate a rod in the locking position:—

Fig. 5 is a similar view except that the rod is in the open position:—

Fig. 6 is an elevation of a card as it will be cut for the name of "W. Smith":—

Fig. 7 is a detail view showing how a bar is locked in a corresponding card perforation, and:—

Fig. 8 is a similar view showing that when the bar is turned 90°, the card is unlocked as far as the particular perforation is concerned.

There is provided an appropriate square or rectangular card cabinet 10 consisting of a frame of sides without top or bottom, which preferably is supported front and back by pivots 11, (only the front pivot is shown), so as to be capable of being turned at last 180°.

In juxtaposition to what may normally be regarded as the bottom of such cabinet are placed a plurality of parallel rods 12 all in the same plane. These rods are characterized in that in section one of their axes is longer than the axis at right-angles thereto.

The foregoing is further characterized in that in section each rod is somewhat pear-shaped, one side being conveniently semi-circular in outline, whilst the remainder tapers to a relatively thin edge (see Figs. 7 and

8). One end of each rod terminates in the form of a circular shaft 13, whilst the other end 14 has a twist of 90°. The twisted ends are adapted to register in bearings 15 fashioned in the corresponding end or side of the cabinet. The effect of the foregoing is that, on pushing the rod in one direction, it is, by virtue of the twist above alluded to, rotated through an angle of 90°, which means that the longer axis, instead of being horizontal, becomes vertical. Conversely, when the rod is pushed in the opposite direction, the rod is turned back through an angle of 90°, so that the longer axis of the rod again becomes horizontal.

It will be preferable to have at least twenty-six of the foregoing rods, namely, one representing each letter of the alphabet. It will be better, however, to provide twenty-seven rods, in which case one can be used to represent a mark of punctuation.

The cabinet will conveniently be marked with the appropriate letters in juxtaposition to the front ends of the corresponding rods. It will also be desirable to provide supports 16 and 17 at the sides of the cabinet for the purpose of guiding the ends of the cards.

The cards used in conjunction with the arrangement that has been described will be perforated as follows. At the top edges of such cards 18, there will be not less than twenty-six but preferably twenty-seven equidistant notches. These notches will each before use in outline be somewhat bottle-shaped. That is to say, there will be a circular curved portion spaced inward from the edge, and extending from the same to the edge will be a narrower parallel neck-like opening.

The manner in which the cards cooperate with the rods 12 for the purpose of holding certain cards in the cabinet while selecting others for inspection will be obvious from the following description. Assuming that it is desired to place in the cabinet a card in respect of a name such as "W. Smith," in this case a card will be placed in an appropriate cutting or punching apparatus in which the whole of the notches other than those representing the letters W, S, M, I, T, H, together with the punctuation mark, will be treated as follows. That is to say, the whole of the other notches will have the shoulders cut away, the neck-like portion of the notch being thereby widened so as to correspond with the full width of the lower portion of the notch. The re-

maining notches, namely, those at 19^w, 19^s, 19^m, 19ⁱ, 19^t, 19^h, 19^r, are not affected. The rods contained in the cabinet are then all pushed so that the longer axes of such rods 5 are vertical (the position shown in Fig. 8). The cabinet being a frame of sides without top or bottom is placed so that the rods are at the lower portion thereof. The card treated as aforesaid (see Fig. 6) is then dropped into 10 position, which means that each of the perforations will register with a corresponding rod. The rods are then pushed in the opposite direction, with the result that the longer axes of such rods now become horizontal (as 15 in Fig. 7). If the cabinet is turned through an angle of 180°, there is the following result, namely, that the card is supported on the rods referenced 12^w, 12^s, 12^m, 12ⁱ, 12^t, 12^h, 12^r, corresponding to W, S, M, I, T, H, punctuation 20 mark, for the reason that the notches corresponding to the other rods have had their shoulders cut away, and therefore no support is afforded by such rods at those points. The cabinet will likewise receive and hold a number 25 of cards, each supported by rods engaging their characteristic notches. When it is desired to remove the card filed under "W. Smith", the appropriate rods are pushed so that the longer axis becomes vertical, with the 30 result that the card is now not supported at any points, as the narrower axes of the rods corresponding to W, S, M, I, T, H, punctuation mark, are narrower than the neck-like portion of the perforations. In consequence, 35 when the cabinet is turned, the particular card falls down and is available for inspection. It will be understood that the remaining cards, having different characteristic notches, will not be affected by the foregoing selective action, and consequently will be retained within 40 the cabinet.

From the foregoing it will be obvious that even though a large number of cards be contained in the cabinet, the result will be identical. Furthermore, assuming that a large 45 number of cards have been removed for inspection, the procedure of turning all the rods to the position shown in Figs. 5 and 8, will allow all of the cards to be dropped into 50 position, and will result in their being all locked by the appropriate rods on the latter being pushed into the position whereby the longer axes become horizontal.

It will be advantageous to provide the 55 notched edge of each card with a small cut placed at one corner as indicated by the numeral 20, the cut on every card being adapted to register with each other, whereby to assure a readily correct positioning of the card 60 within the cabinet.

The rods 12 do not necessarily refer to let-

ters of the alphabet, but may be indicative of other distinguishing characteristics.

I claim:

1. In a selective card cabinet the combination of a locking rod in section having one long and one short axis, a twist of 90° formed at one end of such rod, a bearing to translate the twist into a turning movement, a circular shaft attached to the other end of the rod, and a bearing for supporting the said shaft. 65

2. In a selective card cabinet the combination of a plurality of rods in section having a long and a short axis, means whereby the long axis of the rods can be made to take up 75 either a vertical or a horizontal position, cards each having a plurality of non-lockable edge notches corresponding to some of the rods, and a number of lockable edge notches corresponding to the remainder of such rods. 80

3. In a selective card cabinet the combination of a plurality of rods in section having a long and a short axis, means whereby the long axis of the rods can be made to take up either a vertical or a horizontal position, cards each having a plurality of non-lockable edge notches corresponding to some of the rods, a number of lockable edge notches corresponding to the remainder of such rods, and registering means formed on each card for their 90 correct positioning in the cabinet.

4. In a selective card cabinet a plurality of movable locking rods, each having a portion disposed at substantially right angles to the remainder thereof, and bearings cooperating 95 with the rods to impart a limited rotary motion to said rods with movement of the same.

5. In a selective card cabinet a movable locking rod received within the cabinet and extending therethrough, one end of said rod being twisted at substantially right-angles to the remainder thereof, and means cooperating with said twisted end for causing a limited rotary motion to the rod with movement of the 100 same. 105

6. In a selective card cabinet, locking members each having a portion twisted, means for mounting said members for endwise movement, and means cooperating with said twisted portions of the locking members to cause a turning motion of the latter when moved endwise. 110

7. In a selective card cabinet, a frame, longitudinally movable locking members carried by the frame, a twist formed at one end of said members, and means cooperating with said twist to cause a turning motion of the locking members with longitudinal movement thereof. 115

Dated this 26th day of April, 1927.

WALTER BUCKERIDGE.
